COMBINED HOBBY HORSE AND SUPPORT OR SIMILAR ARTICLE

Leonard F. Johnson, Bristol, Va.

Application October 18, 1954, Serial No. 32,708

Term of patent 3½ years

(Cl. D34—15)

Fig. 2.

Fig. 1.

Fig. 3.

Figure 1 is a side elevation of a combined hobbyhorse and support or similar article, showing my new design, the opposite side having substantially the same appearance;

I claim:

The ornamental design for a combined hobby horse and support or similar article, as shown and described.
